UNITED STATES PATENT OFFICE.

JAMES LYTCHE, OF LAURINBURG, NORTH CAROLINA.

DOOR-CHECK.

SPECIFICATION forming part of Letters Patent No. 268,700, dated December 5, 1882.

Application filed July 5, 1882. (No model.)

To all whom it may concern:

Be it known that I, JAMES LYTCHE, of Laurinburg, in the county of Richmond and State of North Carolina, have invented certain new and useful Improvements in Door-Checks; and I do hereby declare the following to be a full, clear, and exact description of the invention, such as will enable others skilled in the art to which it pertains to make and use the same.

My invention relates to an improvement in checks for doors, gates, shutters, and other similar devices; and it consists in certain details in construction and combination of parts, as will be more fully described, and pointed out in the claim.

In the accompanying drawings, Figure 1 is a perspective view of my improvement secured to a door-frame, and Fig. 2 is a detached 20 view of the check.

A represents a door-frame, and B the door, hinged thereto in the ordinary manner.

My improved check C consists of the stationary semicircular bar a and the vertically-movable semicircular bar a', the latter being secured to the said stationary bar a by the set-screws D. The opposite ends of the stationary bar a are bent or curved at right angles to the main body portion thereof, and provided with openings, by means of which it is secured in position by screws to the door-frame above the door, or to a window-easing above or below the shutters. This bar is either U-shaped or semicircular in form, and is provided at suitable intervals apart with female-screw-threaded openings, in which the set-screws D rest and move. I prefer to use three screws, placed as shown in the accompanying drawings; but any suitable number can be 35 used that will answer the necessary purpose.

The lower ends of these screws D are swiveled to the movable semicircular bar a', and it follows that as the screws D are turned either to the right or left the bar a' is caused 45 to move down or up, as the case may be. The lower bar, a', is similar in shape to the bar a, and is provided with the beveled ends e, which enables the upper edge of the door to move under and engage the plate without meeting any sharp edges, which would injure the same.

The improved check is placed over the door or gate, on the hinge side thereof, and is so situated as to engage the door as soon as it begins to turn on its hinges, and bear thereon throughout its entire movement. The screws 55 D can be turned in the same direction, so as to force the entire bar down, or only one screw D can be turned, so as to cause the bar a' to bear on the door when the latter passes under the depressed portion thereof. When the bar 60 a' is forced downward it bears on the top of the door, and by frictional contact therewith holds the same in any desired position and prevents the same from slamming. The door is free at all times to be moved when sufficient 65 force is used, and the size and construction of the screws D are such as to prevent the plate a' from being moved downward sufficiently to completely lock the door.

Instead of using screws D, as above described, springs can be inserted between the metallic bars a a', and answer all the necessary purposes.

My improvement can be used on gates and window-shutters, and operate in a like manner to that above described. When used in connection with window-shutters the bars a a' could be secured under the shutters, instead of over them, and answer all the necessary purposes.

My improvement is simple in construction, is of few parts, can be manufactured at a small cost, and is durable and effective in use.

Having fully described my invention, what I claim as new, and desire to secure by Letters 85 Patent, is—

The combination, with the plate a, constructed with bent extremities and constructed to be fastened in place, of the bar a', constructed with beveled end, and set-screws D, swiveled 90 in the bar a' and fitted in screw-threaded openings in plate a, substantially as set forth.

In testimony whereof I have signed this specification in the presence of two subscribing witnesses.

JAMES LYTCHE.
